 N. Y., a corporation of New Jersey

Application August 18, 1948, Serial No. 44,959

6 Claims. (Cl. 12—1)

1

This invention relates to an improved footwear pressing machine comprising two relatively thin elastic impervious sheet diaphragms, which are adapted to form an envelope around a laminated article of footwear and compact the plastic and fabric layers of material thereof upon the evacuation of the atmosphere from the envelope. The invention relates particularly to the diaphragm mountings and the power operated mechanism for operating one of the diaphragms to close and open the envelope formed therebetween upon a predetermined time cycle.

Heretofore shoe pressing machines have consisted of a stationary diaphragm and a pivoted diaphragm adapted to form a sealed envelope around the shoe which was pressed by the evacuation of the atmosphere from the envelope. The pivoted diaphragm in such machines was operated manually, and the time each shoe remained in the sealed envelope might be different due to the personal error of the operator. This resulted in some of the shoes being removed from the press before they were sufficiently pressed, and others remaining in the press longer than necessary, which caused defective articles or a loss of production time for both the machine and the operator. Such prior machines also entailed a further loss in time required to change diaphragms when they became worn or punctured. Furthermore such machines were not provided with safety features which are demanded in the present day production.

The footwear pressing machine embodying the present invention is an improvement upon machines of the prior type. The improvements comprise a power actuated mechanism for automatically operating the pivoted diaphragm on a pre-determined time cycle which is adjustable to press the footwear for only the period found to be the most suitable for the specific type of shoe. Thus defective articles of footwear resulting from insufficient pressing and time losses to operator and machine resulting from over-pressing are reduced.

In the operation of the machine, the shoe to be pressed is placed upon the stationary diaphragm while the pivoted diaphragm is in its opened envelope position. The operating cycle of the machine is started by a single movement of the operator, which causes the pivoted diaphragm to move to its sealed envelope position. Then the atmosphere is automatically evacuated from the envelope. After the article of footwear has been pressed for the desired pre-determined period of time by the differential of pressure between the inside and outside of the envelope, the pivoted diaphragm is automatically returned to the

2

opened envelope position, or the starting point of the cycle, without the attention of the operator. The pressed shoe may then be removed from the bottom diaphragm, and the cycle of operations repeated.

For the purpose of further reducing machine and operator time losses, the pressing diaphragms are especially constructed and adapted to be installed quickly in the event replacement may be required by punctures or other defects therein. The machine has been further improved by the addition of safety features, such as safety shields and a diaphragm operating mechanism which keeps the operator's hands away from moving parts and permits the pivoted diaphragm to move to its sealed envelope position solely by the action of gravity, and to its opened envelope position by positively applied power. The weight of the pivoted diaphragm and its frame being relatively small, the gravity closing force is not sufficiently great to injure the operator's or his assistant's hands should they be caught between the pivoted and stationary frames.

The foregoing and other advantages of the footwear press are further described in the following description and the accompanying drawings, in which:

Fig. 1 is a front elevational view of the pressing machine embodying this invention, and showing the pivoted diaphragm in its opened envelope position ready to receive the shoe to be pressed;

Fig. 2 is a side elevational view of the machine shown in Fig. 1;

Fig. 3 is a top plan view of the pressing machine, showing the pivoted diaphragm removed therefrom and a shoe resting on the stationary diaphragm;

Fig. 4 is a plan view of the under side of the pivoted diaphragm mounted in its sub-frame, as it would appear when removed from the main frame and turned through 180° from its sealed envelope position;

Fig. 5 is a cross sectional view taken on line 5—5 of Fig. 2 through the outer edge of the pivoted diaphragm while mounted on the sub-frame and secured to the main frame;

Fig. 6 is a cross sectional view of the outer edge of the stationary diaphragm mounted in its frame and supported on the main frame of the machine, which is taken on line 6—6 of Fig. 3; and

Fig. 7 is a diagrammatic view of the controls for operating the pivoted diaphragm, and automatically controlling the time cycle of the shoe pressing operation.

Referring particularly to Figs. 1 and 2, the shoe

pressing machine embodying this invention comprises a stationary elastic impervious diaphragm 11 mounted in a frame 12 which is supported on the top of the main machine frame 13. A pivotally movable elastic impervious diaphragm 14 is mounted in an upper frame 15 which is pivotally mounted on bearing bolts 16 secured in the frame 13 at each side thereof. The diaphragms 11 and 14 may be made of rubber or rubber composition, including natural or synthetic rubber, or other suitable materials. A lasted shoe 17 containing layers of plastic and fabric to be pressed is placed upon the stationary diaphragm 11, as shown in Fig. 3. The pivotally movable diaphragm 14 is adapted to be moved downwardly over the stationary diaphragm 11, and the larger marginal edges 18 of the pivoted diaphragm are adapted to fit over and be hermetically sealed against the smaller marginal edges 19 of the stationary diaphragm 11 to form an envelope around the shoe 17. The atmosphere within the envelope is evacuated therefrom through a conduit 29 which extends through the stationary diaphragm 11, and is secured thereto by means of a hollow metallic connection 21 hermetically sealed to the diaphragm. The sub-atmospheric pressure created within the envelope causes the outer atmospheric pressure to force the diaphragms 11 and 14 into intimate contact with the outer surfaces of the shoe 17 and thereby compact the layers thereof and evacuate the air that may be trapped between the layers.

The pivoted diaphragm 14 is adapted to descend against the stationary diaphragm 11 solely as a result of the forces of gravity acting thereon. It is adapted to be raised from its sealed envelope position to its opened envelope position, as shown in Fig. 2, by a double acting piston 22 (Fig. 7) connected to a piston rod 23 operating in a cylinder 24, which is pivotally mounted on a bearing 25 at its lower end secured to the base of the machine frame 13. The outer end of the piston rod 23 is pivotally connected by a pin 26 to an arm 27 keyed to a rock shaft 28 oscillatably mounted in the machine frame 13 at its opposite ends. A pair of arms 29 are keyed to the outer ends of the rock shaft 28, and rollers 30 are rotatably mounted on the outer ends of the arms which bear against a bracket 31 on the pivotally movable frame 15. A gravity connection is thereby formed between the actuating piston 22 and the pivoted diaphragm 14. When the piston rod 23 in the cylinder 24 moves outwardly, the rollers 30 roll along the bottom surfaces of the brackets 31, and the pivoted diaphragm 14 thereby may be moved from its sealed envelope position to its upper or opened envelope position as shown in Figs. 1 and 2.

The structure of the apparatus for controlling the piston in the cylinder 24 is shown in Figs. 1 and 2, but the controls are more clearly illustrated in the diagrammatic view in Fig. 7, to which reference is made in the description of the controls. As shown herein the fluid pressure actuated members are preferably operated by air under pressure. The position occupied by the controls in Fig. 7 corresponds to the opened envelope position of the diaphragm 14, as shown in Figs. 1 and 2. In such position, the piston 22 in the cylinder 24 is maintained in its upward position by pressure fluid admitted to the lower end of the cylinder, while the upper end of the cylinder is connected to the exhaust. The piston 22 is reciprocated in the cylinder 24 by alternately admitting and exhausting the pressure fluid to

and from the opposite sides of the piston through the pipes 32 and 33, in which needle valves 35 and 36 are inserted to control the linear speed of the piston 22. The stroke of the piston 22 is cushioned at each end of the cylinder 24 by the ends of the piston 22 restricting the exhaust to the pipes 32 and 33 due to the reduced ends of the piston as they pass over the ports in the cylinder. The admission and exhaust of pressure fluid to and from the pipes 32 and 33, as shown in Fig. 7, is controlled by a master valve 37 containing a piston actuated piston valve 38 reciprocable in the valve casing 39. In the full line position shown, pressure fluid is being admitted from the pressure fluid supply line 40 through the branch 40', the central valve port 41, and the pipe 32 leading to the lower end of the actuating cylinder 24, and pressure fluid has been exhausted from the pipe 33 through the end exhaust valve port 42 to the exhaust pipe 43.

Assuming that the shoe 17 to be pressed has been placed on the stationary diaphragm 11, the pivoted diaphragm 14 is caused to be moved by gravity to its sealed envelope position by reversing the connections of the pressure fluid supply and exhaust lines to the opposite ends of the cylinder 24. The reversal of the connections is made by moving the valve 38 from the position shown in Fig. 7 to the opposite end of the casing 39 where the ends of the valve will occupy the position of the dotted lines 38'. In such dotted line position of the piston valve 38, the pressure fluid supply port 41 in the valve 38 connects the pressure fluid supply line 40 to the pipe 33 leading to the upper end of the cylinder 24, and such port is disconnected from the pipe 32 leading to the lower end of the cylinder 24. In the same position, the end valve exhaust port 44 connects the latter pipe 32 to the exhaust pipe 43'.

The piston valve 38 is reciprocated by the admission of pressure fluid alternately to the opposite ends 45 and 46 of the valve casing 39 against the pistons 47 and 48 on the ends of the valve 38. After the elapse of a given period from the time the valve 38 reaches either end of the valve casing 39, the pressure in the piston chambers at the ends thereof is reduced to atmospheric pressure by the pressure fluid being bled through small passages 49 and 50 in the ends 45 and 46 of the valve casing 39. Therefore the movement of the valve 38 is not impeded, excepting by the force required to expel the residual fluid through the passages 49 and 50.

The movement of the piston valve 38 from the full line position to the dotted line position for the purpose of moving the pivoted diaphragm 14 to its sealed envelope position is manually controlled, and the movement of the valve 38 from the dotted line position to the full line position for the purpose of moving the diaphragm 14 to its opened envelope position is effected by the automatic operation of the piston valve 38. The manual control comprises two valve handles 51 and 52, which are adapted to operate two valves 53 and 54 connected in series between the pressure fluid supply line 40 and the valve piston 47. When the valves 53 and 54 are opened the pressure fluid flows from supply line 40 through the pipe 55 extending to the valve 53, the pipe 56 extending between the valves 53 and 54, and the pipe 57 leading from the valve 54 to the piston 47. The valves 53 and 54 are opened by moving the handles 51 and 52 laterally in any direction, and they are closed by a spring therein (not shown) when the handles are released. The two

valve handles are provided as a safety precaution. In that respect their function is to require the use of both hands of the operator at the same time to start the operation of the machine, and thereby keep the hands of the operator away from all moving parts in which they may be caught. Upon the admission of pressure fluid against the valve piston 47, the piston valve 38 is moved from its full line position to its dotted line position so as to admit pressure fluid to the top end of the cylinder 24 and exhaust it from the bottom end. The piston rod 23 is thereby moved downwardly, carrying with it the diaphragm supporting rollers 30, and the pivoted diaphragm 14 is thereby permitted to descend solely by the action of gravity thereon to its sealed envelope position.

After the formation of the envelope around the shoe 17, the atmosphere is withdrawn from the envelope through the vacuum pipe 20 (Fig. 2), which is adapted to be connected to the main vacuum line 58 by a spring closed cut-off valve 59. The valve is provided with an actuating plunger 60 which is operated by an adjustable pin 61 supported on an arm 62, which is keyed to the rock shaft 28 operated by the actuating piston rod 23. The pin 61 makes contact with the plunger 60 and opens the valve 59 immediately before the end of the downward stroke of the piston rod 23. The degree of vacuum produced in the envelope is registered by a gauge 64 connected by a pipe 65 to the vacuum pipe 20 between the valve 59 and the diaphragm 11.

The vacuum valve 59 remains open during the shoe pressing operation, the duration of which is automatically controlled by the time required for the pressure fluid to build up a pre-determined pressure in a branched pipeline 66 (Fig. 7) connected by a pipe 66a to the pipe 33 which supplies pressure fluid to the top of the cylinder 24. After the predetermined pressure has been reached, pressure fluid from the main supply line 40 is admitted against the piston 48 on the piston valve 38, and moves the latter from the dotted line position to the full line position, so as to reverse the connections of the pressure fluid supply and exhaust lines with the top and bottom chambers in the cylinder 24. The time required for the pressure to build up in the branch line 66 is determined by the rate of flow of pressure fluid through a throttle valve 67 therein, and also by the size of an expansion chamber 68 which is inserted in the branch line between the valve 67 and a valve casing 69, which contains a piston 70 adapted to be operated by the built up pressure in the pipe 66 against a spring 71 and operate a valve 72 connected by a stem 73 to the piston 70. When the predetermined pressure is built up in the pipe 66, the valve 72 is opened, and admits pressure fluid from the main supply line 40, through pipes 40a and 40b, against the piston 48 of the master piston valve 38, and thereby moves it over to the full line position shown in Fig. 7. Upon the upward movement of the piston rod 23, the diaphragm 14 is moved to its opened envelope position, and during the first portion of the movement the vacuum valve 59 (Fig. 2) is permitted to be closed when the pin 61 releases the valve plunger 60.

In addition to the safety features provided by the gravity descending diaphragm 14 and the two operating valves 51 and 52 to prevent the operator from being injured, a shield 75 is attached to the diaphragm operating arm 29 by screws 76 on each side of the machine. The

shield 75 prevents the operator's or his assistant's hands from being caught between the arm 29 and the top of the stationary diaphragm frame 12 when the arm is rocked downward.

For the purpose of reducing the time required for changing the pivoted diaphragm 14 and replacing it with another, the diaphragm is mounted in a sub-frame 77 as shown in Fig. 4, and is adapted to be affixed to the main swing frame 78 as shown in Figs. 2, 3 and 5. The diaphragm 14 is secured in the sub-frame 77 by clamping its marginal edges 79 between lower and upper U-shaped bands 80 of metal with screws 81. The fourth side of the diaphragm 14 is provided with a fold 82 within which is inserted a rod 83.

The underside of the diaphragm 14 is shown in Fig. 4, and the sub-frame 77 in which it is secured is attached to the main swing frame 78, shown in Fig. 3, by turning it through 180 degrees from the position shown in Fig. 4 so that its front edge 84 matches with the front edge 85 of the main swing frame 78. In such position studs 86 on each of the sides of the main frame 78 extend upwardly through holes 87 in the sub-frame 77. As shown in Fig. 2, the sub-frame is secured to the main frame 78 by wing nuts 88 which are turned downwardly on the studs 86. This operation secures three sides of the diaphragm 14 to the main swing frame 78. The fourth side is secured in place by inserting the pins 89 and 90 on the opposite ends of the rod 83 into the sockets 91 and 92 in the bearing bolts 16 for the main swing frame 78. The pin 90 is rigid with the rod 83, and is shorter than the pin 89, which is longer than the depth of the socket 91. The pin 89 is slidable in a bore in the rod 83, and it is pressed outwardly by a spring 93. The pin 89 is retained in the bore in the rod by a pin 94 which operates in a slot 95 in the rod and limits the movement of the pin 89. The rod 83 is secured in the sockets 91 and 92 by first inserting the spring press pin 89 into the socket 91 until the end of the pin reaches the bottom of the socket and then further compressing the spring 93 until the rigid pin 90 can be moved over the face of the socket 92 and inserted therein by reversing movement of the rod 83. The ends of the rod 83 will then be held in the sockets by the action of the spring 93. That construction has the advantage of allowing the rubber diaphragm 14 to be retained in the sub-frame 77 without substantially any tension thereon when the frame is not in use, and when it is installed in the main frame 78, the diaphragm can be placed under tension by stretching the fourth side when the rod 83 is inserted in the sockets 91 and 92. The construction also results in a simplification of the sub-frame 77 so as to bring the pivoted edge of the diaphragm in line with the pivoted axis of the main swing frame 78 which is the correct arrangement for forming a seal between that edge of the pivoted diaphragm and the matching edge of the stationary diaphragm 11.

Due to the construction of the stationary diaphragm 11, it can also be replaced quickly when required. As shown in Figs. 2, 3 and 6 the stationary diaphragm 11 is clamped between two four sided frame members 96 and 97 by screws 98 which extend through the member 97 and are threaded into the member 96. The frame member 97 rests on top of the main frame 13, and the heads of the screws 98 fit into openings 99 in the top flange 100 on the main frame 13.

The fitting 21 which connects the vacuum line 20 to the diaphragm 11 is made of upper and lower parts 101 and 102, between which the diaphragm 14 is clamped by screwing a stem on the upper part 101 into the lower part 102. A stem on the latter part 102 extends through an oversized hole in a plate 103, which is affixed to a cross support 104 by screws 105 (Fig. 3). The stem on the lower fitting part 102 being smaller than the hole in the plate 103, the fitting is capable of wobbling in all directions to permit the diaphragm to adjust itself more accurately to the contour of the shoe when the interior of the envelope is subjected to the sub-atmospheric pressure. In order to remove the diaphragm 11 with its frame 12, the parts 101 and 102 of the fitting 21 are uncoupled, and then the frame can be lifted from the main frame 13, and replaced with another.

While the preferred embodiment of this invention has been shown and described herein more or less in detail, it will be understood that changes in the details thereof may be made without departing from the spirit of this invention and the scope of the appended claims.

Having thus described my invention, what I claim and desire to protect by Letters Patent is:

1. A shoe pressing machine comprising a stationary flexible diaphragm adapted to receive a shoe to be pressed, a pivoted flexible diaphragm having marginal edges adapted to be sealed against corresponding edges of said stationary diaphragm and form an envelope around said shoe, means movable with said pivoted diaphragm for connecting a sub-atmospheric pressure line to said envelope upon said diaphragm reaching said sealed envelope position, means including a prime mover for actuating said pivoted diaphragm from its sealed envelope position to an opened envelope position and supporting said pivoted diaphragm in said opened envelope position, and a gravity connection interposed between said pivoted diaphragm and said prime mover, whereby said prime mover may move independently of said pivoted diaphragm in the direction required to permit said pivoted diaphragm to return by gravity to its sealed envelope position.

2. In a shoe pressing machine, a pivotally actuated pressing diaphragm, a sub-frame to which said diaphragm is secured on three sides, said fourth side of said diaphragm having a bar secured thereto independently of said sub-frame and extending throughout the greater portion of the length of said fourth side, a pivoted main frame for said diaphragm, means for securing said sub-frame to said main frame, and means for securing the ends of said bar on the pivotal axis of said main frame.

3. In a shoe pressing machine having a pivoted diaphragm as in claim 2, wherein said bar comprises a rod which extends through a fold on the fourth side of said diaphragm, a bearing member forming said pivotal axes and having sockets concentric therewith, said bar having projecting ends adapted to be seated in said sockets, and one of said projecting ends comprising a spring pressed detent adapted to be depressed and inserted in one of said sockets to permit the other end of said bar to be inserted in the other socket.

4. In a shoe pressing machine having changeable stationary and pivoted diaphragms, a frame for said stationary diaphragm supported on top of said machine against lateral and downward displacement but freely movable upwards, a sub-

frame for retaining three sides of said pivoted diaphragm, a pivoted main frame, removable fasteners for securing said sub-frame to said main frame, a bar secured to the fourth side of said pivoted diaphragm and having its ends removable from sockets on the axis of the pivotal bearing for said main frame.

5. A shoe pressing machine comprising a fixed frame, a relatively lightweight frame positioned above and pivotally connected to said fixed frame, a flexible elastic diaphragm secured in each of said frames, said diaphragm in said pivoted frame being adapted to be superimposed upon said diaphragm in said fixed frame to form a sealed envelope about a shoe, means for producing a subatmospheric pressure between said superimposed diaphragms, a double acting power piston for operating said pivoted frame, a gravity connection between said piston and said pivoted frame adapted to permit said piston to raise said pivoted frame on one stroke and to move independently of said pivoted frame on its return stroke for lowering said frame to superimpose the diaphragm therein upon said diaphragm in said fixed frame, a control mechanism for said power piston comprising a manually controlled means for admitting pressure fluid against one side of said power piston to lower said pivoted frame, an expansion chamber connected to the said one side of the said power piston, means responsive to the pressure in said expansion chamber for automatically admitting pressure fluid to the other side of said power piston to raise said pivoted frame a predetermined time after said manually controlled means has been actuated.

6. A shoe pressing machine comprising a fixed frame, a relatively lightweight frame positioned above and pivotally connected to said fixed frame, a flexible elastic diaphragm secured in each of said frames, said diaphragm in said pivoted frame being adapted to be superimposed upon said diaphragm in said fixed frame to form a sealed envelope about a shoe, means for producing a subatmospheric pressure between said superimposed diaphragms, a double acting power piston for operating said pivoted frame, a rock shaft actuated by said double acting piston, an arm on each end of said rock shaft, one end of each of said arms being attached to said rock shaft and the other end of each arm being adapted to bear upwardly against said pivoted frame and to move downwardly independently of said pivoted frame, and a plate-like shield attached to each of said arms for protecting the machine operator.

HERBERT R. POLLEYS.
